Primary Examiner — Eric Goodman(74) *Attorney, Agent, or Firm* — Buchanan Ingersoll & Rooney PC(57) **CLAIM**

The ornamental design for a gasket for injector, as shown and described.

DESCRIPTION

FIG. 1 is a perspective view of a gasket for injector showing our new design;

FIG. 2 is a front elevational view thereof, a rear elevational view being a mirror image thereof;

FIG. 3 is a left side view thereof, a right side view being a mirror image thereof;

FIG. 4 is a top plan view thereof;

FIG. 5 is a bottom plan view thereof; and,

FIG. 6 is a cross-sectional view taken along the line of VI-VI of FIG. 2.
